UNITED STATES PATENT OFFICE.

ALFRED HEALD, OF PHILADELPHIA, PA., ASSIGNOR TO HUGH McCALLUM,
ORLANDO CREASE, AND ANDREW J. SLOAN, OF SAME PLACE.

DESIGN FOR CARPETS.

SPECIFICATION forming part of Design No. 11,609, dated January 20, 1880.
Application filed December 22, 1879. Term of patent 3½ years.

To all whom it may concern:

Be it known that I, ALFRED HEALD, of Philadelphia, Pennsylvania, have invented a new and original Design for a Carpet, (Case E².) of which the following is a specification.

My design for a carpet is fully shown in the accompanying photographic illustration.

The design comprises scroll-work and scroll-figures, arranged in respect to each other as shown, so as to imitate stems, leaves, and blossoms of a conventional character, the particular nature of the ornamentation being too fully shown to need detailed description.

Irrespective of the colors employed, I claim—
The design for a carpet, said design comprising scroll-work and figures imitating stems, leaves, and blossoms, all substantially as described, and as shown in and by the accompanying illustration. 15

In testimony whereof I have signed my name to this specification in the presence of two subscribing witnesses.

ALFRED HEALD.
